(57) **CLAIM**

The ornamental design for a combustion engine intake manifold for snowmobiles and all terrain vehicles, as shown and described.

DESCRIPTION

FIG. 1 is a rear perspective view showing my new design for a combustion engine intake manifold for snowmobiles and all terrain vehicles;

FIG. 2 is a front elevational view of the intake on a combustion engine in phantom broken lines;

FIG. 3 is a rear elevational view;

FIG. 4 is a front elevational view;

FIG. 5 is a right side elevational view;

FIG. 6 is a left side elevational view;

FIG. 7 is a bottom plan view; and,

FIG. 8 is a top plan view.

The broken line drawings of the combustion engine are for the purposes of illustrating environmental structure only and form no part of the claimed design.
